UNITED STATES PATENT OFFICE

WILLIAM L. WALLIS, OF COLLEGE PARK, GEORGIA

DESIGN FOR A SMOKER'S STAND OR SIMILAR ARTICLE

Application filed October 29, 1932. Serial No. 45,631. Term of patent 14 years.

To all whom it may concern:

Be it known that I, WILLIAM L. WALLIS, a citizen of the United States, residing at College Park, in the county of Fulton and State of Georgia, have invented a new, original, and ornamental Design for a Smoker's Stand or Similar Article, of which the following is a specification, reference being had to the accompanying drawing, forming part thereof.

The figure is a perspective view of the smoker's stand showing my new design.

I claim:

The ornamental design for a smoker's stand or similar article, as shown.

WILLIAM L. WALLIS.
